Filed July 7, 1966, Ser. No. 563,441
9 Claims. (Cl. 248—350)

ABSTRACT OF THE DISCLOSURE

An article supporting device comprising a support which is readily adjustable in size, preferably made of an inflatable material, such as rubber, which will retain its general contours during its various inflated sizes, such as the shape of a human head for supporting wigs, and which may be readily deflated for storage, and has a rigid base support.

This invention relates to an article supporting device, and particularly to wig stands which may be adjusted for the support of different sizes of wigs.

An object of the present invention is to provide an improved, simplified, and sturdy article supporting device.

Another object of the present invention is to provide an improved article supporting device which is readily adjustable in size to accommodate the support of different sizes of articles.

A further object of the present device is to provide an improved wig display stand which is inflatable to different sizes to provide for the support of different sizes of wigs.

Further objects and advantages of this invention will become apparent from the following description referring to the accompanying drawing, and the features of novelty which characterize this invention will be pointed out with particularity in the claims appended to and forming a part of this specification.

In accordance with the present invention, an improved article supporting device is provided which comprises an inflatable article supporting member, which, in the case of a wig stand, is made in the general shape of a human head attached to a neck portion. The neck portion of the device is adapted to have a snug frictional supporting engagement within a collar of a supporting base. Preferably the base is formed with an enlarged flange which extends radially outwardly to a larger diameter than the collar, so as to provide greater stability to the supporting device. Such an inflatable article supporting device, not only provides a very useful article display stand, but most conveniently provides a form of shape retainer which is readily deflated for ease in transportation and inflated for supporting the article, such as a wig, when not in use. Various details of the improved article supporting device will be more readily understood from the following description of the illustrated embodiment in the accompanying drawing in which:

FIG. 1 is a perspective view of an embodiment of the present invention, particularly adapted for use in supporting wigs;

FIG. 2 is a perspective view of the inflatable member of the wig stand shown in FIG. 1, as seen from the left rear side thereof, and removed from the supporting base;

FIG. 3 is a perspective view of a demountable base collar of the type shown in FIG. 1;

FIG. 4 is a perspective view of a base mounting flange to which the collar shown in FIG. 3 is adapted to be secured for providing a base of the type shown in FIG. 1; and

FIG. 5 is a perspective view, partly broken away, of an assembly of the collar in FIG. 3 in the mounting flange shown in FIG. 4.

Referring to the drawing, an article supporting device embodying the present invention is illustrated in the form

2

of a wig stand. This wig stand comprises an inflatable article supporting member, which, in this instance, is in a form having the general contour of a head 10 extending from a neck portion 11. Preferably this inflatable supporting member is formed of a material, such as rubber, which is expansible under inflation, so that the head portion 10 can be expanded within predetermined desired limits to provide for supporting various sizes of wigs corresponding to various similar sizes of heads. The neck portion 11 is provided with an inflating tubular connection 12 for providing for the admission and discharge of inflating medium, such as air, into and from the wig supporting member.

In order to provide for a convenient means of mounting the wig supporting member, a supporting base is provided which preferably is formed of two demountable parts as shown in FIGS. 3 and 4 and made of any suitable rigid material, such as wood, plastic, or metal. This supporting base preferably includes a collar 13 which is adapted to be demountably secured in any suitable manner to a supporting flange base member 14, as by threaded engagement of the lower threaded portion 15 of the collar 13 with a complementary threaded collar 16, integral with the flange base member 14. If desired, the supporting base can be made as a single integral unit.

The collar 13 of the supporting base also preferably is formed with a plurality of circumferentially spaced apertures 17. These apertures 17 may be decorative to some degree, but perform a very practical function, in that the inflated neck 11 will tend to bulge outwardly into the apertures when it is inserted into the collar 13, thereby forming a readily releasable arrangement for securing the inflated article supporting member in stable relationship to the mounting base. Normally, the inflated neck 11 will have a snug frictional engagement within the collar 13, which also will lend stability to the support of the head 10 on the base. Preferably, the inflating tube 12 is positioned in the neck 11 relative to its base so that when it is assembled in the collar 13, the inflating tube 12 will extend outwardly through one of the apertures 17, as shown in FIG. 1. With such an arrangement, the inflating tube 12 can readily be sealed by a stopper 18 insertable in the opening of the tube 12. The stopper also preferably is attached to the collar 13 by a suitable band 19, or similar element, in order to prevent its being misplaced or lost. If desired, the stopper 18 can be dispensed with and a suitable valve mounted directly in the mouth of the inflating tube 12 for preventing accidental discharge of inflating medium while providing for the controllable discharge of medium from the inflated wig stand by any suitable valve sealing nozzle structure. Also, the inflating tube 12 can be located elsewhere on the article supporting member, such as extending into the neck at a position which would normally be above the collar 13, or it could extend out of the bottom of the neck 11. This convenient inflating and deflating feature provides a portable wig stand which can readily be deflated and packed in travel baggage, and, on reaching a desired destination, it can be reinfated to hold a wig after it is removed from the wearer's head, so as to keep the wig in proper shape.

Preferably, article positioning and retaining means are additionally provided on the surface of the article supporting member 10, and these may comprise a plurality of the protuberances in the form of beads 20. These beads are preferably arranged in circumferentially spaced relationship, extending generally around the head 10, nearer the top of the head on the side thereof adjacent to the portion corresponding to a face and extending somewhat lower on the opposite back side of the head, whereby a wig is adapted to being held in substantially the position of a scalp on a head. Preferably, also, these beads 20 extend as a plurality of circles, and, as shown in FIGS. 1

and 2, these two circles preferably are eccentrically arranged closer together towards the top front side of the head, and farther apart towards the back of the head. It is not essential that the head 10 have a face thereon, but this may be found to add to the attractiveness of a display of wigs on such supporting devices when used in places such as store windows, sales counters, and beauty salons.

While a particular embodiment of this invention has been illustrated and described, modifications thereof will occur to those skilled in the art. It is to be understood, therefore, that this invention is not to be limited to the particular details disclosed, and it is intended in the appended claims to cover all modifications within the spirit and scope of this invention.

The invention claimed is:

1. An article supporting device comprising an inflatable article supporting member having means for admitting an inflating medium into said member and for preventing the accidental discharge of the medium while providing for controlled discharge of the medium therethrough, and means comprising a supporting base having a part into which a portion of said article supporting member extends in snug frictional engagement therein when inflated for retaining said supporting member in position, said part of said base being formed as a collar extending upwardly 20 from a larger sized support member and having means for receiving said inflation medium admission means comprising an aperture in the side of said collar.

2. An article supporting device comprising an inflatable article supporting member having means for admitting an inflating medium into said member and for preventing the accidental discharge of the medium while providing for controlled discharge of the medium therethrough, and means comprising a supporting base having a part into which a portion of said article supporting member extends in snug frictional engagement therein when inflated for retaining said supporting member in position, said article supporting member having the general contours of a head when inflated and being provided with means in addition to said contours for positioning and retaining an article on said member.

3. A supporting device as defined in claim 2 wherein said article positioning and retaining means comprises a series of spaced protuberances arranged in a predetermined configuration.

4. A supporting device as defined in claim 6 wherein said series of protuberances are arranged in a plurality of spaced circles.

5. A supporting device of the type defined in claim 2 wherein said article positioning and retaining means comprises a series of spaced beads arranged in a plurality of different diameters.

6. A supporting device of the type defined in claim 5, wherein the eccentricity of said circles is such as to place the circles lower on one side of said head and closer together toward the top of the head whereby the support is particularly adapted to retain a wig in substantially the position of the scalp on a head.

7. A wig stand comprising an inflatable wig-supporting member made of collapsible material adapted to be inflated to the general contours of a head on a neck and having an inflating medium admission and discharge nozzle, means for controllably sealing the nozzle, means comprising a rigid hollow collar for receiving the lower end of said neck and said neck being of such size when inflated for providing a snug tight retaining fit within said hollow collar, said collar having an aperture in the side thereof into which aperture said nozzle is fitted, a mounting base, and means for removably mounting said collar on said base.

8. A stand as defined in claim 7 wherein said head member has a part depicting a face and is provided with a plurality of spaced wig positioning and retaining beads on the side and top of said head member away from said face and corresponding to the scalp portion of the head.

9. A stand as defined in claim 8 wherein said retaining beads are arranged as a pair of eccentric circles of different diameters closer together toward the top forepart of the head whereby a wig is adapted to be held in substantially the position of the scalp of the head.
